UNITED STATES PATENT OFFICE.

WILLIAM C. WHITNEY, OF NEWARK, NEW JERSEY, ASSIGNOR TO SILAS E. WILMORE, OF NEW YORK, N. Y.

VENDING-MACHINE.

No. 818,594.

Specification of Letters Patent.

Patented April 24, 1906.

Application filed March 17 1904. Renewed February 17, 1906. Serial No. 301,636.

To all whom it may concern:

Be it known that I, WILLIAM C. WHITNEY, a resident of Newark, in the county of Essex and State of New Jersey, have invented certain new and useful Improvements in Vending-Machines; and I do hereby declare the following to be a full, clear, and exact description of the invention, such as will enable others skilled in the art to which it appertains to make and use the same.

My invention relates to an improved vending-machine, the object of which is to provide an improved machine in which a great variety of goods of different price can be vended and provide a display-receptacle for each and every variety of goods contained therein.

A further object is to provide an improved vending-machine which will be neat and attractive in appearance to tempt the public to buy, which will deliver the goods in a clean and wholesome manner, which will give every purchaser the goods desired or return his coin to him, and if any column of goods is exhausted will automatically display the fact.

With these objects in view the invention consists in certain novel features of construction and combinations and arrangements of parts, as will be more fully hereinafter described, and pointed out in the claims.

In the accompanying drawings, Figure 1 is a view in elevation, showing a portion of the front casing removed. Fig. 2 is a view in vertical section. Fig. 3 is a front view of coin-controlling mechanism with certain parts removed. Fig. 4 is a view in horizontal section. Fig. 5 is an enlarged view illustrating the segment-locking mechanism. Fig. 6 is an enlarged view illustrating detailed construction of parts operated by the shaft 77. Figs. 7, 8, and 9 are enlarged views of the coin-guide 41, holder 57, and parts carried thereby. Fig. 10 is a view in section of the five-cent chute. Figs. 11, 12, 13, and 14 are detail views of the coin-holder 57. Figs. 15 and 16 are views illustrating the cover-securing mechanism. Fig. 17 is a view in section of the operating-knob. Fig. 18 is a top view of the storage-frame. Fig. 19 is a plan view of the star-wheel; Fig. 20, a view of the ejector, and Fig. 21 a view of the carton or box.

I represents a cylindrical casing secured within a circular flange 2 on a base-plate 3, and the upper edge of said cylinder 1 is provided in opposite sides with inclined slots 4

to receive pins 5 on a recessed ring 6 when the latter is turned slightly, and a spring-catch 7 is secured at one end to the casing 1 and projects across a slot. This spring-catch 7 is bent or flared to permit its displacement by a pin 5 and is made with an opening 60 to receive the pin and lock the ring 6 over the cylinder. The ring 6 has secured therein a conical glass or other transparent cover 8, to the open center of which a metal collar 9 is secured and forms a bearing for the vertical shaft 10, the lower end of this shaft having a thrust-bearing on antifriction-balls 11 in a cup 12 on base-plate 3. The extreme upper end of this shaft 10 is made with an annular recess to provide a shoulder against which the central hub of a knob or handhold 13 is secured by means of a screw 14, screwed into the upper end of the shaft 10 and having its head bearing against knob 13, and to compel the rotation of the shaft when the knob is turned the shaft at its annular shoulder is made with lugs 15 to enter corresponding notches in the hub of knob 13. This shaft 10 is further supported against lateral bending or displacement by a cross-bar 16, having a central bearing to receive the shaft and secured at its ends upon brackets 17, affixed to the interior of cylinder 1 by means of screws 18.

On shaft 10 my improved storage-frame 19 is secured and holds the cartons or boxes containing the goods to be vended. This frame 19 comprises at its top a circular open-work plate or casting 22, secured centrally upon shaft 10, and to which the bent or flanged upper ends of radial partitions 20 are secured by screws or rivets, as shown. These radial partitions also pass through a central cylinder 21, secured to plate 22, and has secured therein at its lower end a hub 23, secured to shaft 10 by a set-screw. Flanged plates 24 are secured to the opposite sides of the partitions 20 at their lower ends, forming bottom supports for the cartons or boxes, and are spaced apart to provide a passageway between them for the ejector 25, which will be hereinafter explained. Cross-plates 26 connect the partitions 20 near their bottom at their outer edge, and shutters 27 are hinged to these plates 26 and are fastened in an upright position by spring-clips 28 on plate 22 to partially inclose the cartons or boxes, but are sufficiently narrower than the compartments or columns to permit a view.

of the same and to provide clearance for protruding fingers 29 on weights 30, the function of which will be hereinafter explained. The plates 26 are spaced sufficiently from bottom plates 24 to allow a single carton or box to be forced out, and the central cylinder 21 terminates above bottom plates 24 far enough so as not to interfere with the movement of the ejector in forcing out the bottom carton.

10 The central cylinder 21 is in reality in a horizontal section a polygon having a flat side at the inner side of each column or compartment, thus giving to the compartment in cross-section a general keystone shape to receive cartons of like shape and utilize to the greatest extent the space of the frame, and this is an improvement over all machines of this character heretofore known.

Beneath the transparent cover 8 a conical display-tray 31 is secured by means of a set-screw 32, passed through a central hub 33 on said tray and against shaft 10 to receive the tray thereon. This display-tray is provided with a series of radial display-compartments 35 for the goods vended, a compartment being located directly above each and every column of the storage-frame 19, so as to display the goods contained in the cartons of said compartment and which will be secured if 30 this compartment is turned to the front and the proper coin dropped into the machine.

Should a column or compartment become emptied, the weight 30 of such column will of course rest on bottom plates 24, when the outwardly-projecting finger 29 thereon will be in a horizontal plane to engage a cam-plate 34. This cam-plate 34 is hinged at one side to the inner wall of what I term the "front" casing 35, in which is contained the 35 coin-controlled mechanism to be hereinafter explained. The plate 34 has cams at both ends, so that it will be engaged and depressed by a weight-finger 29 if the storage-frame is turned in either direction, and to the free 40 end of this cam-plate 34 a rod 36 is pivotally connected and passes up through front casing 35 and is secured to one side of the central pivotal support of a disk 37, upon which the word "Empty" or other like information 45 is printed. When the cam-plate 34 is depressed by a weight-finger 29, the rod 36 will be pulled down to turn disk 37 to a position to display the word "Empty" at an opening or window in front casing 35, and thus advise 50 the purchaser that this column is empty. When the storage-frame is turned to free the cam-plate 34, a weight 38 on one side of disk 37 will return the parts to their former positions and leave a blank at the opening or 55 window, or suitable printed matter may be exposed to indicate that goods are in the column in front.

The front casing 35 is provided with coin-slots, labeled, respectively, "1 cent," "5 cents," and "10 cents," so that the purchaser

knows in which to insert his coin. Communicating with these slots are grooved coin-chutes 39 of just sufficient width to accommodate the proper coin—as, for instance, should a one-cent coin or ten-cent coin be placed in the five-cent chute it will fall through the open bottom down into a carton delivery-pocket 40, formed in the bottom of front casing 35 in convenient reach of the purchaser. Beneath the inner ends of these coin-chutes 39 a coin-guide 41 is located, over which, unless deflected, the coins would jump into a hopper 42, which conveys them to the delivery-pocket 40, and to compel the passage of the proper coin into guide 41 I provide a deflector 43, which is in the form of a bell-crank lever pivoted at its angle and normally held behind the "1-cent" chute by a spring to guide a one-cent coin into the guide and is provided with suitable stop-pins 43^a to limit its movement in both directions. To the shorter member of the deflector 43 a depending rod 44 is secured and is connected at its lower end to one end of an approximately horizontal lever 45, pivoted between its ends 40 on a pin or lug made integral with a bracket 46, secured to base-plate 3. The inner end of lever 45 is provided with a double cam-plate 47 in the path of screws 48, projecting down through a star-wheel 49, secured on shaft 10 95 by a set-screw. This star-wheel 49 has a point or projection for each and every compartment, and each point of the star has a screw-threaded opening to receive a screw 48, and while I have shown screws in all the 100 points it is evident that no screws are needed for the one-cent columns, as the deflector is normally behind the one-cent chute. The screws 48 for the ten-cent columns are the longest and depress the cam-plate 47 the 105 greatest distance, as the deflector must be thrown to its extreme position behind the ten-cent chute. The screws for the five-cent columns are shorter than those for the ten-cent goods and move the cam-plate and deflector behind the five-cent chute. Hence it 110 will be seen that when the storage-frame is turned to bring a column to the front the screws automatically bring the deflector behind the proper chute and coins placed in the 115 wrong chute will jump over the guide 41 into hopper 42 and fall into the delivery-pocket. It will thus be seen that the value of the 120 goods in the several columns, or, in other words, the price necessary to secure the goods in the various columns, can be changed at will by simply shifting the screws—that is to say, changing short screws for longer ones, and vice versa.

To outwardly-projecting lugs 50 on the front plate of coin-guide 41 the turned-up ends of a plate 51 are pivoted by screws 52, and this plate has at its upper edge three coin-deflectors 53, normally in position to direct a coin into guide 41; but a rod 54 con-

nects an arm 55 on one end of this plate with the rod 36, so that when said rod is pulled down by the finger-weight, as above explained, the plate 51 will be swung on its 5 pivot to locate the deflectors 53 over the coin-guide 41 and in the path of the coins to prevent a coin from entering the guide 41 when an empty column is in operation, but deflect the same into the carton delivery-pocket 10 below.

The lower end of coin-guide 41 is contracted, and upright lugs 56 on my improved coin-holder 57 are pivoted thereagainst to give to the holder its necessary pivotal freedom. This holder 57 comprises two plates 15 secured together by screws and spaced apart by enlargements. A set-screw 58 in a depending arm 59 on guide 41 is adapted to exactly position said holder 57 above a segment 20 60, and a spring 61 holds the guide in such position and returns it thereto.

Between the plates of holder 57 and pivoted at one end to one of them is a coin-ejector 62, having a slot 63 in its lower free end, in 25 which is located a pin 64 on a bell-crank lever 65, pivoted to the outside of the holder, a slot 66 being provided therein, in which the pin 64 moves. This lever 65 is connected by a rod 67 with one end of a bar 68, shaped as 30 shown and pivoted to a fixed cylinder 69. This bar 68 has an inclined slot 70 therein, forming a cam-face against which a pin 71 on one side of a plunger 72 bears. This plunger 72 is mounted in a fixed cylinder 69, in which 35 a coiled spring 74 is located to normally hold the plunger in one extreme position, and to the opposite end of the plunger one end of a ratchet-lever 75 is pivotally secured. The ratchet-lever 75 is pivoted between its ends 40 and has a roller 76 at its free end, bearing against the periphery of star-wheel 49, so that it will be seen when the storage-frame and star-wheel are turned the roller end of ratchet-lever 74 will move back and forth 45 over the teeth or points of the star-wheel. This motion is communicated to plunger 72 and through the medium of pin 71 against the cam-face of slotted bar 68 causes longitudinal movement of rod 67 and pivotal movement 50 of lever 65, which in turn swings the coin-ejector 62 to throw out any coin in holder 57. Hence if a purchaser, for instance, places a one-cent coin in the machine while the storage-frame is set to vend a one-cent article 55 and he then attempts to turn the machine to a five or ten cent column the coin will be promptly thrown out by ejector 62 and returned to him in the delivery-pocket. This is also the case where a purchaser without 60 intention to defraud changes his mind about the goods he desires after he has placed the coin in the machine. By turning the storage-frame he will have his coin returned, as above explained, and can purchase what he 65 desires.

77 represents the operating-shaft horizontally mounted in front casing 35 and projecting through the same at one side, where it has a crank-arm 98 secured thereon to be turned by the purchaser to eject the goods he 70 desires. The segment 60, above referred to, is secured on this shaft 77 directly below coin-holder 57, which latter holds a coin in position on the segment in front of a shoulder 78. This shoulder is preferably formed by means 75 of a detachable block, which can be conveniently replaced in the event of wear.

A pin 79 projects from one side of segment 60 and is engaged by the notched or hooked end of a pivoted locking-pawl 80, which prevents rotary movement of the segment 60 and shaft 77 until a coin is in position on the segment, when the holder 57 and segment 60 through the medium of its shoulder 78 are temporarily coupled together, so that a rotary movement of shaft 77 and segment 60 will move the holder pivotally far enough to compel a pin 81 on one edge of the holder to swing locking-pawl 80 out of the path of pin 79 and permit a continued movement of the 90 segment. The coin will jump the shoulder 78 and when the segment moves to its extreme position will drop down behind the same into a hopper 82 for directing the coins into a coin-receptacle 83 in the bottom of casing 1.

A disk 84 is secured upon shaft 77, and upon its face outwardly-projecting screws or pins 85 are located, two of said screws or pins being provided and spaced the proper distance 95 apart. An arm 86 is loosely pivoted at one end on the shaft 77 between collars 87 and is disposed between the screws or pins 85 and moved thereby. The lower end of this arm 86 is connected by a pitman 88 with a sliding 105 block or carriage 91, mounted to slide in a slotted guide-frame 90, secured to base-plate 3. To a lug 90 at one side of this block or carriage 91 the ejector 25 is pivoted and held in its inclined position by a coiled spring 93, 110 located between the ejector and a shoulder 94 on the block or carriage.

When the shaft 77 is permitted to turn by the coin-controlled mechanism above explained, the first rotary motion is not communicated to arm 86, as the shaft turns partially before a screw or pin 85 engages the arm. This is to give the coin-controlled mechanism at segment 60 sufficient time to unlock the locking-pawl 80. The continued movement of shaft 77 swings arm 86 downward and forward to draw the carriage 91 and ejector 25 forward, compelling the latter to engage the lowest carton or box 95 and force it forward onto an inclined plane 96, 125 down which it falls to the delivery-pocket. This delivery-pocket has a toothed guard 97 at its inner upper end to prevent the introduction of a hand or tool through the delivery-pocket to the interior of the machine. After 130

the carton or box 95 falls into the delivery-pocket the operator releases the crank-arm 98, when a coiled spring 99, secured to one side of disk 84, returns the parts to their former 5 positions.

To prevent a purchaser from turning the storage-frame after he has inserted a coin and started to turn the operating-shaft 77, I provide the disk 84 with a V-shaped notch 100 in 10 its periphery, into which the angular end of a curved lever 101 is located when the parts are in their set position. The lever 101 is pivoted between its ends and connected at one end by a rod 102 with a catch-bar 103, hinged 15 at one end. This catch-bar 103 is notched at one end, so that when it is raised its notched portion will be in front of ratchet-lever 75 and lock the same against pivotal movement, hence locking the star-wheel 49 and preventing 20 the turning of the storage-frame. This upward and locking movement of catch-bar 103 is effected just as soon as disk 84 begins to turn, as one end of the lever 101 is forced out against the periphery of the disk, which 25 movement elevates the other end of the lever and rod 102 to swing the catch-bar 103 to its locking position and maintain it in such position until the disk returns to its former position, so that the end of lever 101 can enter 30 the V-shaped notch 100 therein. Another disk 104 is secured upon shaft 77 adjacent to the side wall of front casing 35 and made with ratchet-teeth recesses 105 at the ends of the toothed section. At least two notches 35 105 are necessary, one notch at each end of a series of ratchet-teeth. In order, however, to insure the proper placing of the disk 104 on the shaft 77 and also to provide new teeth when one series become worn, I prefer to provide 40 the disk with four notches 105 and provide the periphery of the disk with several series of notches. A triangular pivoted dog 106, normally located in a recess 105, is adapted to engage the ratchet-teeth when the 45 shaft is turned to compel a complete operation thereof before return. Against the upper face of this triangular dog 106 a spring-pressed plate 107 bears, said plate being secured upon a rod 108, mounted in a bracket 50 109, secured to front casing 35, and a coiled spring 110 is located on the rod between the bracket and plate to yieldingly hold the latter against the dog 106. When the disk 104 turns, its first function is to tilt the triangular dog 55 106, which movement is permitted by spring-pressed plate 107. The dog thus engages the ratchet-teeth in an inclined position, which will permit the turning of the disk in but the correct direction until the extreme of 60 movement is reached, when the dog will be in another recess 105, and its inclination will change to permit the return of the disk and shaft to their former positions.

By reference to Figs. 2, 3, and 10 it will be seen that a depending deflector 111 is hinged

in the five-cent chute. This deflector 111 when a five-cent coin is placed in the chute will be swung up thereby and the coin pass into the coin-guide 41, and should a coin smaller than a five-cent piece be inserted in the five-cent chute it will fall through the open bottom thereof, as it is too narrow to reach to the ledges or grooves at the sides of the chute; but it has been found that if a one-cent coin be poised in the five-cent slot and given a sharp blow its momentum will be sufficient to carry it to the coin-guide 41, and to prevent this deflector 111 is located in the five-cent chute, against which a smaller coin will strike and be deflected into the delivery-pocket 70 75 80 below.

A removable door 112 is provided in casing 1, through which access can be had to the storage-frame to fill the columns and to gain access to the cash-receptacle, and a section of 85 front casing 35 is made removable to gain access to the coin-controller mechanism, both of said removable sections being securely locked in their closed positions, but capable of removal when the proper key is used. 90

The operation of my improvements is as follows: We will suppose the purchaser desires five-cent goods. He grasps knob 13 and turns the storage-frame until the proper column is at the front ratchet-lever 75, serving to properly center the column. By so moving the storage-frame the screw 48 in star-wheel 49 will depress cam-plate 47 and compel the deflector 43 to move behind the five-cent chute, so as to deflect a five-cent 100 coin into coin-guide 41, down which it falls onto the segment 60 and is supported in an upright position by the holder 57, which latter is coupled to the segment by the coin. Should coins be deposited in the other chutes, 105 they would jump over guide 41 and fall into the delivery-pocket, and should a smaller coin be entered in the five-cent chute it will either fall from the chute or strike the deflector 111 and be ejected therefrom into the delivery-pocket below. With the segment 60 and holder 57 coupled together by the coin, shaft 77 can be turned by crank-arm 98, the first movement being to force the holder 57 inward to move the locking-pawl 80 out of 110 locked engagement with the segment, when the shaft 77 will be free to turn. The turning of shaft 77 through the medium of screws or pins 85 serves to draw arm 86 forward and pull the carriage 91 with the ejector 25 thereon forward. The ejector 25 engages the lowest carton or box and forces it out from the column into the delivery-pocket, and the coin falls from segment 60 down into the coin-receptacle. When arm 98 is released, 115 spring 99 will return all the parts to the normal positions, ready for the next purchaser. When a column is empty, the weight-finger 29 will engage cam-plate 34 and move disk 37 to designate the fact at the open window 120 125 130

and will move the deflectors 53 in front of coin-guide 41 to deflect any into the delivery-pocket which may be inserted when an empty column is in operative position. If 5 the storage-frame is moved after a coin has been inserted, the ejector 62 will be operated to throw out the coin, and after the shaft has begun its movement the lever 101 through the medium of catch-bar 103 will 10 lock the ratchet-lever 75 and prevent movement of the storage-frame. It will thus be seen that my improved machine is honest to itself and to the public, for it cannot cheat a purchaser nor can a purchaser cheat it.

15 A great many slight changes might be made in the general form and arrangement of the parts described without departing from my invention, and hence I would have it understood that I do not restrict myself to 20 the precise details set forth, but consider myself at liberty to make such slight changes and alterations as fairly fall within the spirit and scope of my invention.

Having fully described my invention, what 25 I claim as new, and desire to secure by Letters Patent, is—

30 1. In a vending-machine, the combination with a casing, of a vertical shaft therein having means outside of the casing to turn the same, a storage-frame secured on said shaft and adapted to contain cartons or boxes with goods therein, a star-wheel on said shaft, and a ratchet - lever engaging the periphery of said star-wheel.

35 2. In a vending-machine, the combination with a casing, of a vertical shaft therein having means outside of the casing for turning said shaft, a storage-frame secured on the shaft and adapted to contain goods to be 40 vended, a star-wheel on said shaft, a ratchet-lever engaging the star-wheel, and means for locking said lever in locked engagement with the star-wheel when ejector mechanism is operated.

45 3. In a vending-machine, the combination with a casing, of a rotary storage-frame therein, a star-wheel movable with the frame, a ratchet-lever pivoted between its ends, a roller at one end of said lever engaging the 50 star-wheel, an ejector, a shaft to operate the ejector, and means for locking said lever in locked engagement with the star-wheel to hold the storage-frame when the shaft is operated.

55 4. In a vending-machine, the combination with a rotary storage-frame and a star-wheel fixed thereto, of a ratchet-lever pivoted between its ends and one end engaging the periphery of the star-wheel, a pivoted locking- 60 bar having a notched end to be moved in the path of the lever and hold it in position to lock the star-wheel and frame, an ejector-operating shaft, a disk thereon having a notch or recess in its periphery and a lever having 65 one end normally in said notch or recess and

when the disk is turned to move the lever out of the notch adapted to raise the locking-bar to lock the ratchet-lever.

5. In a vending-machine, the combination with a casing having an opening or window 70 therein, of a rotary storage-frame for goods to be vended comprising a series of radial columns for goods, weights located on top of each and every column of goods, and an indicator, and devices connected with said indicator and operated by a weight in any empty column, to move the indicator and designate 75 the fact of any empty column at the opening or window.

6. In a vending-machine, the combination 80 with a casing having an opening or window therein, of a rotary storage-frame in said casing having a series of radial columns for goods to be vended, a weight in each and every column on top of the pile of goods, a 85 counterweighted rotary disk behind the window having the word "Empty" or other like printed matter thereon normally out of alignment of the window, and means operated by a weight in an empty column for turning the 90 disk to expose the word "Empty" at the window.

7. In a vending-machine, the combination with a casing having an opening or window in its front, of a counterweighted rotary disk 95 behind the window having the word "Empty" thereon normally out of alignment with the window, a rotary storage-frame in the casing having a series of radial compartments for goods to be vended, a weight on top of the 100 goods in each and every column, a finger on each weight projecting out beyond the frame, a double cam-plate pivoted at one end and in the path of a weighted finger in an empty column to be depressed thereby, and a rod connecting the free end of this cam-plate with the disk to turn the latter and display the word "Empty" at the window when the cam-plate is depressed by a weighted finger.

8. In a vending-machine, the combination 110 with a rotary vending-frame comprising a top plate, a series of radial partitions secured to the top plate, a cylinder secured to the central portion of the top plate, depending therefrom and through which the inner edges of 115 the partitions pass, a ring or disk secured in the cylinder near its lower end, bottom plates secured to the lower ends of the partitions at opposite sides providing a space for an ejector between them, plates connecting 120 the outer edges of the partitions but spaced from the bottom plates to allow a single carton or box to pass below them, shutters hinged to said outer plates, and catches on 125 the top plate to secure the upper ends of said hinged shutters.

9. In a vending-machine, the combination with a casing, a vertical shaft therein, and a storage-frame secured on said shaft, of a removable cover on said casing through which 130

the shaft projects, inwardly-projecting pins on a depending flange of the cover, to enter inclined slots in the casing, and a spring-metal tongue over one of said slots having an opening to receive and lock a pin and bent to permit its displacement by the pin in entering the slot:

10. In a vending-machine, the combination with a column or receptacle for a pile of cartons or boxes to be vended, of a sliding block or carriage below the same, an ejector pivoted at one end to one side of the block or carriage, a spring to hold the ejector in an inclined position to engage the inner end of the lowest carton, a rotary shaft, an arm swung by said shaft, and a pitman connecting said arm and carriage or block.

11. In a vending-machine, the combination with a fixed ejector-guide, and a sliding ejector thereon, of a storage-frame comprising a series of radial columns or compartments any one of which may be disposed in front of the ejector, a rotary shaft, an arm loose thereon, a disk secured to the shaft, pins or screws on the face of said disk on opposite

sides of the arm to move the same, and a pitman connecting the arm with the ejector to move the latter when the shaft is turned.

12. In a vending-machine, the combination with a shaft to operate the ejector mechanism, of a disk on said shaft having a series of teeth on its periphery and a recess at both ends thereof, a triangular dog mounted to turn on pivot and having one of its points normally in a disk - recess, a longitudinally-movable rod, a plate thereon against a face of said triangular dog and a spring pressing said plate against the dog to hold it in an inclined position to compel the disk to be turned throughout the entire series of teeth before it can return or until the dog shall enter the recess at the end of the teeth and its position be reversed.

In testimony whereof I have signed this specification in the presence of two subscribing witnesses.

WILLIAM C. WHITNEY.
